UNITED STATES PATENT OFFICE.

MAX SCHNEIDER, OF DOOS, NEAR NUEREMBERG, GERMANY.

DRAFT-REGULATING DEVICE FOR STOVES OR FURNACES.

SPECIFICATION forming part of Letters Patent No. 399,085, dated March 5, 1889.

Application filed November 5, 1888. Serial No. 289,990. (No model.)

To all whom it may concern:

Be it known that I, MAX SCHNEIDER, a subject of the Emperor of Germany, residing at Doos, near Nuremberg, in the German Empire, 5 have invented certain new and useful Improvements in Draft-Regulating Devices for Stoves or Furnaces, of which the following is a specification.

This invention relates to improvements in 10 draft-regulating devices for stoves or furnaces; and the object of this invention is to effect the regulating of the energy of the fire in a most simple but efficient way by operating the dampers for regulating the area of the passages of the air and the products of combustion by means of a single handle. I attain 15 this object by the mechanism illustrated in the accompanying drawings, in which—

Figure 1 represents a vertical section of the 20 lower part of a magazine-stove provided with my improved device. Fig. 2 is a horizontal section of an angular slide or gate, which serves to regulate both the ingress of air to the grate and the egress of the results of combustion to the base-flue of the stove. Figs. 3 25 and 4 are vertical sections of the stove, showing the regulating device in different positions; and Figs. 5 to 8 illustrate a modification of both the regulating device and the base of 30 the stove.

Similar letters refer to similar parts throughout the several views.

A is the damper or gate, placed in front of the stove underneath the ash-pit or in the 35 door of the latter, serving to regulate the area of the passage of the air to the combustion-chamber and the passage of the products of combustion to the base-flue of the stove. In cross-section this damper forms a right angle, 40 the vertical part *a* of which is adapted to cover the air-passage in front of the stove, while the horizontal part *b* is provided with a notch, *b'*, admitting the passage of the products of combustion through the base-flue to 45 the chimney *D*. The notch *b'* is so arranged that when the air-passage in front of the stove is opened the passage through the horizontal division *B* is closed, and vice versa. The direct communication of the combustion-chamber *C* with the chimney-flue is admitted 50 through the opening *c'* and regulated by means

of the hinged damper *c*, which is actuated by the handled rod *d* through the intermediation of the lever *h*. The latter is connected with its upper end to the hinged damper *c*, and engages at its lower end by a pin, *d'*, with the rod *d*, passing the damper *A*, where it is provided with a handle outside of the stove.

As the rod *d* freely passes the damper *A*, the damper *c* may be actuated independently 60 of the damper *A* and without regard to its position. However, it must be understood that whenever the air-passage at *a* begins to open, the communication with the base-flue must have been discontinued, in order to prevent 65 the fresh air from entering into the base-flue of the stove. The lateral movement of the gate *A* is determined by logs attached to the body of the stove. This combination of the regulating elements with another is of considerable importance, because a part of the carbonic-oxide gases accumulating within the upper part of the stove is permitted to escape into the chimney-flue in any position of the damper *A*. If the slide *b* is duly regulated, an intensive smoke-consuming is effected, as the gases generated by the combustion are forced by the natural draft of the chimney to pass the glowing fuel upon the grate on their way to the base-flue *m* and the 80 chimney-flue *n*, when the damper *c* is closed, and the mechanical effect is thereby considerably increased. However, care must be taken in this case that the air-passage will be entirely closed, and in order that no mistake 85 can happen the slide *b* and the damper *a* are either formed in one piece or they are so intimately connected by means of the rod *d* that the position of the slide *b* simultaneously determines that of the damper, as heretofore 90 mentioned, Figs. 1 to 3. In case that the fire shall be kept slowly burning without radiating heat to the walls of the stove the air-passage has to be entirely closed and the damper *c* opened by moving the rod *d* into the position 95 shown in Fig. 4 of the drawings.

A slightly-modified arrangement of the regulating elements is represented by Figs. 5 to 8, wherein both the passages *a'* and *b'* for the air and the carbonic-oxide gases are placed in 100 the horizontal wall *B*, separating the base-flue *m* from the interior of the stove. In conse-

quence of this arrangement a channel, a^2 , is adapted to conduct the outer air through the passage a' into the combustion-chamber, and the gate A is formed as a circular oscillating disk provided with corresponding slots to admit the circulation of the air and of the products of combustion, in the manner as heretofore set forth with reference to Figs. 1 to 4 of the drawings.

Having now fully described my invention and in what manner the same is to be performed, I declare that what I desire to claim and secure by Letters Patent is—

1. As an improvement in draft-regulators for stoves, the combination of the gate having apertures for the passage of air and the carbonic-oxide gases, the handled rod for operating said gate, the hinged damper, and the lever connected to said damper and to said rod, substantially as set forth.

2. As an improvement in draft-regulators, the combination, with a magazine stove or furnace having a lower base-flue, of the gate having a front aperture for the passage of air and a lower aperture for the passage of the carbonic-oxide gases, the handled rod loosely connected to said gate, the upper hinged damper, and the lever connected to said damper at its upper end and to said rod at its lower end, substantially as set forth.

In testimony that I claim the foregoing as my invention I have signed my name, in presence of two witnesses, this 16th day of October, 1888.

MAX SCHNEIDER.
